UNITED STATES PATENT OFFICE.

ALEXANDER McLAREN, OF DAYTON, OHIO.

ICE-CREAM-CONE DISPENSER.

1,297,205.

Specification of Letters Patent. Patented Mar. 11, 1919.

Application filed July 22, 1915. Serial No. 41,391.

To all whom it may concern:

Be it known that I, ALEXANDER McLAREN, a citizen of the United States, and resident of Dayton, county of Montgomery, State 5 of Ohio, have invented certain new and useful Improvements in Ice-Cream-Cone Dispensers, of which the following is a specification.

The present invention relates to means particularly adapted for dispensing ice cream cones or articles of similar cup-like form that are commonly packed in nested series in a single container or holder.

The object of the invention is to provide 15 means by which an original package of such articles can be supported on a counter or table and the articles successively withdrawn therefrom, all of such articles being constantly protected from dust or other 20 contaminating influences.

In the accompanying drawings—

Figure 1 is a perspective view of an apparatus constructed in accordance with the invention;

Fig. 2 is a perspective view of the package the contents of which are to be dispensed;

Fig. 3 is a similar view of the package showing the delivery end thereof opened;

Fig. 4 is a vertical section through the apparatus when in use;

Figs. 5 and 6 are details.

Referring to the drawings, 1 designates the casing or carton of a package of ice 35 cream cones, the latter being arranged in nested form so that a relatively large number may be transported in a package of moderate dimensions. As shown, the carton 1 is, as usual, provided at its ends with flaps 40 3 which may be folded outwardly to open the end of the casing from which it is desired to withdraw the cones 2. Preferably, as shown, there are four of these flaps, the casing 1 being alike at both ends so that the 45 series of cones may be introduced into the container from either end although it will be understood that the articles are only designed to be withdrawn from the end toward which the points of the cones are 50 directed.

As shown, the package comprising the container 1 and the nested articles therein is arranged in upright position on a stand or support having an apertured top through 55 which the cones 2 may be withdrawn. Pref-

erably the stand or support is made in the form of a box-like casing having an opening in one side which is normally closed by a swinging door 4 through which it is possible to reach the lowest cone 2 of the package which projects through the aperture in the top of the stand.

5 designates suitable yielding means shown as consisting of a plurality of light coiled springs which extend across the aperture in the top of the stand in such relation as to engage the lowest cone 2 of the series with sufficient force to support the same and the series of cones resting thereon. It will be understood that by a slight 65 downward pull the lowest cone will be withdrawn from engagement with the springs 5 and the latter caused to automatically engage the next higher cone of the series.

The package of cones is retained in vertical position on the stand or support by suitable means. As shown, these means comprise a plate or block 7, which may be of metal having an aperture corresponding in form and size to the cross-sectional shape of 80 the cone case 1 and this plate or block is adapted to rest on the outwardly bent end flaps at the lower, open end of the casing 1 and clamp the same against the top of the supporting stand. Lateral movement of 85 the package of cones is prevented and the open end thereof is retained in proper alignment with the aperture in the top of the support by providing on said support a plurality of upwardly extending pins 8 adapted to enter corresponding sockets or passages 9 in the block 7.

The manner of using and the advantage of the means hereinbefore described will be readily understood and appreciated. It will 95 be seen that the invention provides a very simple means by which ice cream cones or similar articles may be dispensed from the original packages, without exposing any of such articles to dust or insects until 100 the package has been completely emptied. When a package has been emptied another can be instantly substituted. The invention provides means whereby it is unnecessary to touch or directly handle the cones after the 105 same have been packed in the cartons or cases at the factory until they are to be used. The advantage of this will be readily appreciated. The case or container in which the cones are packed at the factory is 110

utilized as a part of the dispensing apparatus so that the number of parts and cost thereof is reduced to a minimum.

Having thus described my invention what 5 I claim is:—

1. An apparatus for dispensing articles of the character referred to comprising a stand or support having a top provided with a suitable aperture, a carton or case having its 10 lower end open, and communicating with the aperture in the stand top, and having laterally extending flaps at said lower end, means for pressing each of said flaps close against the top of the stand surrounding 15 the aperture therein and thus holding the carton or case in position on the stand, and effectually closing the same against the entrance of dust, and means arranged to support a series of nested articles within the 20 carton and permit the successive withdrawal thereof through the aperture in the stand top.
2. An apparatus for dispensing articles of the character referred to comprising a stand or support having a top provided with a suitable aperture, a carton or case having its lower end open, and communicating with the aperture in the stand top, and having laterally extending flaps at said 25 lower end, an apertured block adapted to be slipped freely over the outer end of the carton and clamping the flaps at the lower end 30

thereof against the top of the stand to completely protect the interior of the carton from the entrance of dust, means for preventing movement of the carton and said block laterally of the stand, and means arranged to support a series of nested articles within the carton and permit the successive withdrawal thereof through the aperture 40 in the stand top.

3. An apparatus for dispensing articles of the character referred to comprising a stand or support having an aperture formed in its top and provided with a plurality of upwardly extending studs, a carton or case having its lower end open and communicating with the aperture in the stand top, and having laterally extending flaps at said open end, said flaps being separated one from another to straddle the said studs, a block surrounding the lower end of the carton and engaging said studs, and clamping said flaps close against the top of the stand, and means arranged to support a series of nested articles within the carton and permit the successive withdrawal thereof through the aperture in the stand top.

In testimony whereof I affix my signature.

ALEXANDER McLAREN.
